UNITED STATES PATENT OFFICE.

ROBERT J. STOKES, OF TRENTON, NEW JERSEY.

BRAKE-SHOE.

1,165,143.

Specification of Letters Patent. Patented Dec. 21, 1915.

Application filed December 30, 1914. Serial No. 879,673.

To all whom it may concern:

Be it known that I, ROBERT J. STOKES, a citizen of the United States, and a resident of Trenton, county of Mercer, State of New Jersey, have invented certain Improvements in Brake-Shoes, of which the following is a specification.

One object of my invention is to improve the construction of brake shoes and the lining therefor.

A further object of the invention is to design the shoe so that the lining can be forced into the shoe under pressure and retained in place.

15 A still further object of the invention is to arrange the layers of lining material prior to being pressed into the shoe so as to avoid uneven or raw edges.

These objects I attain in the following 20 manner, reference being had to the accompanying drawings in which:

Figure 1 is a perspective view of a brake shoe, showing the lining in position; Fig. 2 is a side view of the same; Fig. 3 is a vertical sectional view; Fig. 4 is a perspective view of the shoe prior to inserting the lining; Fig. 5 is a sectional view, showing the method of arranging the layers of lining material prior to being forced into position; and Fig. 6 is a perspective view of one 30 of the strips of material which is used in carrying out my invention.

Referring to the drawings, 1 is the brake shoe having a recess 2 with undercut flanges 3 at each side and also having a series of barbs 4, which are also undercut, and which are distributed over the surface of the shoe, as shown in Fig. 4. At each side of the shoe are flanges 5 which retain the material laterally. The material, as illustrated in Fig. 6, 40 consists of a series of sets of woven asbestos fiber, as at 6, having a series of metallic wires 7 longitudinally arranged therein and this material is impregnated with a rubber composition, or its equivalent, which ties the fibers firmly together and provides a suitable surface for the brake lining. I lay no claim to this composition as it may be modified considerably without departing from 45 the essential features of the invention. In fact, I lay no claim to the asbestos cloth and reinforcing wires as these may also be modified.

50 The cloth 6 is cut into strips of the proper length and one is preferably laid upon another until the desired number of plies is

attained and the ends are bent, as shown in Fig. 5, the abutting ends being on the inside of the shoe, as illustrated in said figure. The joints may be on the same line or may be staggered without departing from the spirit of the invention. By this arrangement of the plies of the material, I provide a lining in which there are no rough edges which are likely to be frayed out as the fabric is continued around each end.

A suitable die is provided of a shape to conform to the finished outer surface of the lining, the shape being clearly shown in Fig. 1. The lining is subjected to about two thousand pounds pressure to the inch, which will cause the laminated lining material to be forced into the cavity 2 of the brake, as illustrated in Fig. 3, and while under pressure it is vulcanized by steam in the ordinary manner until it is thoroughly set, after which the pressure is removed and the result is a lining accurately fitting the cavity of the shoe and held in the cavity by the undercut edges and the undercut prongs. As there will be no free ends of the fiber exposed, the surface will wear away evenly and will provide a lining which will be able to withstand the hard usage to which it is subjected.

While I have shown the lining as applied to a shoe or head of a particular shape, it will be understood that the shoe or head may be modified according to the use to which the invention is to be applied.

I claim:

1. The combination of a brake shoe having an undercut cavity and a lining consisting of asbestos fiber combined with metallic wires and impregnated with a cementitious material, the material being forced into the undercut cavity and shaped under pressure, the bearing surface of the lining extending beyond the shoe.

2. A brake shoe having a cavity and undercut projections; a lining consisting of a series of woven laminated sections formed of asbestos and reinforcing wires and held together by a cementitious material, said laminated sections being forced into the cavity of the shoe and shaped under pressure.

3. The combination of a shoe having a recess with undercut projections; a fibrous lining consisting of a series of layers of woven fabric, the layers being turned in at each end with the abutting edges on the in-

side and pressed into the cavity and shaped to conform to the lines thereof.

4. A brake shoe having a recess with undercut ends and a series of undercut projections; a fibrous lining consisting of a series of layers of asbestos reinforced with wire and adhesive material, the said layers being bent inward with the raw edges abutting so as to provide continuous unbroken

fibers at each end when the lining is pressed into the proper shape and vulcanized.

In testimony whereof I have signed my name to this specification in the presence of two subscribing witnesses.

ROBT. J. STOKES.
